UNITED STATES PATENT OFFICE.

ROBSON C. GREER, OF LEBANON, PENNSYLVANIA.

ORE ROASTING AND CALCINING FURNACE.

SPECIFICATION forming part of Letters Patent No. 508,542, dated November 14, 1893.

Application filed July 26, 1892. Serial No. 441,272. (No model.)

To all whom it may concern:

Be it known that I, ROBSON C. GREER, a citizen of the United States, residing at Lebanon, in the county of Lebanon, State of Pennsylvania, have invented certain Improvements 5 in Ore Roasting and Calcining Furnaces, of which the following is a specification.

My invention relates to furnaces intended more particularly for desulphurizing ores. 10 Heretofore some furnaces of this class have been constructed with an annular roasting chamber surrounding and communicating with a central stack; the ore in such case being heated by a series of separate and independent openings or combustion chambers 15 formed in the outer wall.

The main purpose of my invention is to provide a simple form of roasting furnace which will produce a thorough and uniform 20 treatment of the ore; and this I effect by means of the improved construction herein-after fully described in connection with the accompanying drawings, the novel features of which are specifically pointed out in the 25 claims.

Figure 1 is a sectional elevation of a circular furnace or kiln embodying my invention. Fig. 2 is a half-cross-section on line X X of Fig. 1 and Fig. 3 is a similar section on line 30 Y Y of Fig. 1. Figs. 4 and 5 illustrate a modified construction.

The furnace shown in Figs. 1 to 3 is represented as of the usual circular form. The central cylindrical chamber A which forms in 35 connection with the upward extension h, the smoke stack of the furnace, is surrounded by a wall a having numerous apertures a' arranged at an angle so as to open upwardly into the central chamber; and a passage g in the base 40 of the furnace provides access for cleaning. The annular roasting chamber B formed between the stack wall a and the intermediate wall b, is provided as usual with a feed opening f' at the top and with ore drawing openings or chutes f at the bottom. This wall b is provided with numerous apertures b' corresponding with those in the wall a but inclined in the opposite direction so as to open 45 downward into the roasting chamber. Between the wall b and the outer wall c of the furnace is formed another annular chamber which extends from practically the highest

point of the ore chamber B to near the bottom of the latter. This third chamber C is adapted to serve as a single large combustion 55 chamber wherein the fuel gases are ignited and consumed, and from which the products of combustion are brought, by means of the numerous openings b', into intimate contact with every portion of the mass of ore stored 60 in the chamber B, through which they must pass in order to reach the stack A.

The gas chamber D, by means of which the heating is effected, circles the entire roaster and forms the base of the combustion chamber C into which a series of ports d open from it while gas is fed to the chamber D from any convenient source through the connection d'. Air ports e and e', the latter passing to the rear of the gas chamber, open into the combustion chamber adjacent to and on opposite sides of each gas inlet d, thus insuring an intimate blending of air with the lighted gas; peep holes c' are also provided at numerous points in the outer wall from which the plugs 75 which close them may be readily removed if an additional supply of air to the chamber C is required to insure perfect combustion. Thus far the construction is identical with that shown, described, and claimed in my pending application, serially numbered 424,620. Air may be supplied to the ports e, e' either directly through openings e² in the outer 80 wall, as in the construction disclosed in the above-mentioned case or through vertical passage ways E arranged in close proximity to the combustion chamber C, extending the whole height of said chamber and communicating with an annular air chamber E' located directly over the combustion chamber; air 85 being admitted to said air chamber and highly heated therein and in the vertical passage ways E before issuing from the mouths of the ports e, e' into the combustion chamber.

In the modified form of furnace shown in 95 Figs. 4 and 5 the latter being a cross-section through Y Y of Fig. 4, the arrangement of all the chambers is substantially the same as in Figs. 1 to 3 but the usual circular form with the stack in the center is departed from, the 100 structure being rectangular with the stack at the rear, and the ore-roasting chamber lying between it and the combustion chamber and communicating with both as in the previously

described construction. This form of furnace is more cheaply constructed than the circular and equally embodies all the features of my invention.

5. By means of my improved construction not only is a very simple form of furnace produced requiring but a single gas chamber and a large combustion chamber extending the full height of the roasting chamber but better and 10 more economical results are produced in operating it; the large combustion chamber and the facility with which a sufficient amount of air is admitted to it, insure superior combustion, and the uniformity with which the entire contents of the roaster are treated due to 15 the direct communication at all points of its height with the combustion chamber, greatly increases its capacity and the thoroughness of the work.

20. What I claim is—

1. In an ore roasting or calcining furnace, the combination with the stack, the combustion chamber, and the ore roasting chamber located between the combustion chamber and 25 stack, and having communication on one side with said combustion chamber and on its opposite side with said stack, of the gas chamber D located at the base of said combustion chamber and having exits d, and air passages 30 E having inlet ports near the top of the combustion chamber and outlet ports adjacent to said gas exits, substantially as set forth.

2. In an ore roasting or calcining furnace, the combination with the stack, the combustion chamber, and the ore roasting chamber located between the combustion chamber and stack and having communication on one side with said combustion chamber and on its opposite side with said stack, said combustion 35 and ore roasting chambers being of substantially the same height, of the gas chamber D located at the base of said combustion chamber and having exits d, and air passages E having inlet ports near the top of the combustion chamber and outlet ports adjacent to 40 said exits d, substantially as set forth.

3. An ore roasting or calcining furnace, having a rectangular stack, a rectangular combustion chamber, and a rectangular ore 50 roasting chamber, said roasting chamber being located between said combustion chamber and stack and communicating on one side at different points in its height with said stack and on its opposite side at different 55 points in its height with the combustion chamber, said combustion and ore roasting chambers being of substantially the same height, substantially as set forth.

4. In an ore roasting or calcining furnace, 60 the combination with the rectangular stack, and rectangular ore roasting chamber, of a rectangular combustion chamber having communication with said roasting chamber, said

combustion chamber having in its base a gas chamber D with gas exits in the top of same 55 and also having air ports adjacent to said gas exits, substantially as set forth.

5. In an ore roasting or calcining furnace, the combination of the rectangular stack, the rectangular ore roasting chamber communicating therewith, and the rectangular combustion chamber communicating with said ore roasting chamber, said ore roasting chamber being located between said combustion chamber and stack, and said combustion 70 chamber having in its base a gas chamber D with gas exits in the top of same and also air inlet opening into it adjacent to said gas exits and air inlets opening into it at various points, substantially as set forth. 80

6. In an ore roasting or calcining furnace, the combination with the rectangular stack, of the rectangular ore roasting chamber, the rectangular combustion chamber, said roasting chamber being located between the combustion chamber and stack and having communication with both of the same, and said combustion chamber having in its base a gas chamber D with gas exits in the top of the same and air passages E with inlet ports near 90 the top of the combustion chamber and outlet ports adjacent to said gas exits, substantially as set forth. 95

7. The combination, in an ore roasting and calcining furnace, with the stack, and the ore roasting chamber communicating with said stack, of the combustion chamber having communication with the ore roasting chamber, and a gas chamber, located in the base of said combustion chamber and having 100 gas exits in its top, the wall of said combustion chamber being formed to provide air passages, E with inlet ports near the top of the combustion chamber and outlet ports adjacent to said gas exits, substantially as described. 105

8. In an ore roasting and calcining furnace, the combination of the rectangular stack and the rectangular combustion chamber, located at opposite sides of the furnace, with the rectangular roasting chamber between said stack and combustion chamber, said combustion and roasting chambers being of substantially the same height and said roasting chamber having communication on one side at different points in its height with said combustion chamber and on its opposite side at different points in its height with said stack, substantially as described. 110 115

In testimony whereof I affix my signature in presence of two witnesses. 120
